UNITED STATES PATENT OFFICE.

WILLIAM McMANE AND BENJAMIN F. CARPENTER, OF SUMMIT, NEW JERSEY.

TRUCK-LADDER.

1,090,222.

Specification of Letters Patent. Patented Mar. 17, 1914.

Application filed October 30, 1912. Serial No. 728,722.

To all whom it may concern:

Be it known that we, WILLIAM McMANE, residing at 9 South street, Summit, Union county, New Jersey, and BENJAMIN F. CARPENTER, residing at 22 Elm street, Summit, Union county, New Jersey, both citizens of the United States, have invented certain new and useful Improvements in Truck-Ladders, fully described and represented in the following specification and the accompanying drawings, forming a part of the same.

The present invention relates to a counterbalanced aerial safety ladder and truck combined with means for supporting a hose upon an extension ladder and turning the same in any direction. This is effected in the present invention by mounting a turntable for the ladder in an elevated position upon the side-frames of the truck, which frames are trussed to give them the requisite strength.

To facilitate the manipulation of the ladders and the hose if attached thereto, the ladder is fully balanced by means of an extension-foot which projects downward through the turntable when in use and is weighted to balance the ladder and provided with means for increasing the weight to balance the hose and firemen when required.

To permit the ladder when in an inclined position, to swing around the entire circle, the side-frames of the truck have open arches beneath the turntable so as to clear the weighted foot of the ladder when it is inclined and turned in various directions.

The elevation of the turntable brings the fulcrum of the ladder a considerable distance, as ten or twelve feet, above the ground, which permits the foot to project this distance from the fulcrum, and gives the counterbalance weight a great leverage, so that less weight is necessitated to balance the ladder.

The turntable rests upon anti-friction bearings so that it can be easily moved by hand-gearing to any required position, and as the ladder is balanced it can also be tipped by hand-gearing to any desired angle. The turntable is fitted to an annular seat upon the top of the side-frames, the seat having a gap upon the middle line of the truck, and the truck having a clear space between the side-frames in line with said gap through which the weighted foot can be extended downward when the ladder is moved from a horizontal to an upright position, which

may be effected wholly by the influence of the weighted foot.

A great advantage in the adjustment of the hose is secured by attaching it near its nozzle to the extreme end of the extension ladder, and providing supports upon the main ladder through which the hose can slide when the extension ladder is projected.

To facilitate the movement of the turntable when the ladder is inclined, the hose is preferably extended through an aperture in the turntable to the ground upon which sufficient coils may be arranged to permit the projection of the extension ladder, and the end of such coils connected to a hydrant or fire-engine. The extension ladder is commonly projected while the main ladder is in an upright position, and such arrangement of the hose when empty permits the projection of the ladder and the inclining and turning of the ladder to any required position for using the hose.

The mechanism for turning the turntable, for inclining the ladder, and holding it in such inclined position, are thus enabled to operate without any great stress and are therefore never in danger of breaking. The counterbalance thus affords security in the manipulation and use of the ladder, which is the most important consideration in the use of such a device, with persons upon it.

Braces upon the truck are arranged, when the ladder is erected for use, to project materially beyond the sides of the truck and thus greatly extend its base, and effectually brace it against all danger of overturn by extending the base well beyond the center of gravity of the elevated ladder and combined weights.

A central tie or reach connects the ends of the truck below the turntable, thus keeping the arches effectively from spreading under the load upon them. Such provision for increasing the base of support is of great importance, as the irregularities of street surfaces and the difficulty of finding secure positions for the placement of such an apparatus, especially in the confusion and urgency of a dangerous conflagration, render it often impossible to secure a level place for the location of the truck.

By fully counterbalancing the ladder, it is enabled to safely reach great heights and great horizontal distances, so as to meet the most urgent cases; and the construction is such that all the movements as to heights

and positions are under the control of one operator standing upon the turntable where he can see and work with precision.

The invention includes spring-cushions 5 pressed against the ladder when in transportation to hold it steadily, and other details of construction, all of which will be understood by reference to the annexed drawing, in which—

10 Figure 1 is a plan of the apparatus; Fig. 2 a side elevation of the same, both views showing the ladder adjusted horizontally for transportation. Fig. 3 is an elevation of the top of the cushioned ladder-support, 15 with ladder resting thereon; Fig. 4 is a cross section of the truck at the center of the turntable; Fig. 5 is a plan of the turntable with the cap-ring omitted, and one edge of the turntable broken away adjacent to the 20 gate; Fig. 6 is an edge view of the turntable-seat with its gate; Fig. 7 is a side view of the gearing for working the ladder-slanting device; Fig. 8 is a front view of the guide-box for the side-brace; Fig. 9 is a plan of 25 the same in section on line 9—9 in Fig. 10; Fig. 10 is a section on line 3—3 in Fig. 8; and Fig. 11 is a section on line 4—4 in Fig. 10. Fig. 12 is a cross section at the center of the turntable, showing the ladder inclined transversely to the truck-frame; and 30 Fig. 13 is a cross section of the truck-frame where the lifter-yokes are pivoted thereon. Fig. 14 shows the hose-connections to the ladders.

35 The truck is shown with side-frames having level ends a , a' connected by an arch formed with sloping sides b , b' and top-beam c . The sides and top of the arch are trussed by beams d and braces d' . The side- 40 frames are connected by cross-bars a^2 and stiffened by diagonal braces a^3 , and the arches are trussed and prevented from spreading by a central tie-bar or reach c' which connects the ends of the truck across 45 the middle of the arch, and is held as near the ground as is practicable by struts c^2 projected downward from the tie-beams a^2 nearest the base of the arch.

50 Wheels A, A' are shown under the ends a , a' of the truck, and the wheels used for steering are preferably made to turn under the ends of the truck-frame. Hand-wheels B and B' are shown upon the opposite ends of the truck-frame to be used for steering. 55 The truck may be propelled by any desired means.

The turntable e is mounted upon an annular seat f upon the side-frames at the top of their arches, and the main ladder C is pivoted to the turntable on pivot-bearings e' at opposite sides of a gap g through which the foot C' of such ladder can swing downwardly upon its pivot. The foot has a weight C² to counterbalance the ladders, 60 when not extended. The extension ladder 65

D may be arranged to slide upon the main ladder C in any convenient manner and extended by any suitable means, as the usual rope and a windlass c^4 . The seat f has a corresponding gap g' on the axial line of the truck, and the space between the side-frames of the truck is unobstructed next such gap so that the foot of the ladder can swing downwardly between the frames to attain an upright position. The seat f is provided with anti-friction rolls r beneath the turntable and with rolls r' at its periphery, and a cap-ring h is secured upon the seat f and provided with anti-friction rolls r^2 . The turntable is thus supported by rolls against 75 strain in every direction.

The seat f at each side of the gap is rabbed to receive ears k , k' upon the ends of the gate f^4 , the ear k being pivoted by bolt i to form a hinge upon which the gate can be 80 swung outwardly, as indicated by the full lines f^4 in Fig. 1, so as to wholly open the gap. The ear k' is secured, when the gate is in use, by a removable bolt j .

The gate completes the annular structure 90 of the ring and is provided with the rolls r , r' and r^2 ; and its lower inner edge is provided, like the remainder of the annular seat, with cog-teeth l , to which a pinion l' is fitted for turning the turntable. The 95 shaft of the pinion extends upward through the turntable and a bearing l^2 , and is provided upon the top with a hand-wheel l^3 . A bracket m is extended downwardly from the turntable to sustain a rack-bar or other 100 "pusher" for controlling the movements of the ladder after it is moved to an upright position by the counterweight.

A windlass upon the bracket controls certain movements of the ladder as hereinafter 105 described. The bottom of the bracket is provided with a journal n fitted movably in a bearing n' upon the reach, to resist the strain upon the windlass and pusher.

A rack-bar m' is shown in Figs. 1, 3 and 110 7, actuated by a pinion m^2 connected with a hand-wheel m^3 above the turntable by gearing m^4 . The axle m^5 of the pinion is fastened in the bracket m and the pinion turns thereon with the last cog-wheel of the gearing m^4 . A yoke m^6 having rolls l^6 therein guides the rack-bar in its movements. The yoke enables the rack-bar to tip in an inclined position to which it is moved by the 115 upward swinging of the foot.

The rack-bar has a hook m^7 upon its front end to engage a coupling-pin m^8 on the ladder, and has a button m^9 to hold it thereon, and it thus moves the foot when the rack is propelled by the pinion m^2 and hand wheel m^3 . When adjusted, the ladder may be locked by a screw l^6 in the bearing l^2 . The rack-bar furnishes a positive connection to the ladder as shown in Figs. 7 and 12, to lower the ladder about 45 degrees 120

from the vertical; the side-bars of the main ladder having a notch o' to clear the truck-frames, when the ladder is lowered any farther.

- 5 Each side of the ladder is strengthened by an iron-plate o^2 shown in Figs. 2 and 3, where the pivot is inserted and the notches are cut out. A hose y may be carried on the truck and extended as shown in Fig. 14, 10 through the gap in the turntable at the under side of the ladder, and through one or more clamps y' upon the main ladder to a clamp y^2 near the outer end of the extension ladder, where it is furnished with a nozzle y^7 . The hose hangs in a loop between the clamps y' and y^2 , (as shown in dotted lines y^4 in Fig. 14) until the extension ladder is projected.

15 A branch fixture is applied to the hose on the ladder C , and a branch-hose y^5 with a nozzle is extended from such fixture for use by an operator independently of the nozzle supported upon the extension ladder. A cock y^6 cuts off the branch-hose when not required for use. When the ladder is extended over the axis of the truck it can be lowered to a horizontal position by opening the gate f^4 of the turntable-seat; and during such lowering movement the ladder is moved 20 by reducing the counterbalance and is controlled by a rope n^5 secured to the main ladder, as shown in Fig. 2, and let out or drawn in by an operator having it wound several times around a stationary bar n^4 to give it a 25 frictional resistance. When the ladder reaches an upright position, the rack-bar is coupled thereto and its movements thereafter are positively controlled by the rack-bar at any angle within 45 or 50 degrees of 30 the vertical.

40 A windlass n^2 is journaled upon the lower end of the bracket m and a rope n^3 is extended therefrom and connected to the foot C' .

45 The windlass shaft is provided with two cranks l^5 so that two men are enabled to operate it at once, and its axle is furnished with a ratchet-wheel l^4 and a movable pawl l^3 by which the windlass may be locked 50 when it is necessary to hold the ladder in any required position by the rope n^3 with the ladder D extended.

55 The hand-wheels l^2 and m^3 are journaled upon the turntable, where an operator can stand and manipulate them, and at the same time view the entire length of the ladder and move and guide it intelligently.

60 Supports are provided beneath the main ladder and its foot when it is horizontal, the rear support p consisting of a standard with cheek-pieces q at the top between which the main ladder lies, and elastic cushions q' arranged between such cheek-pieces, against which the side-bars of the main ladder impinge when it is lowered. The front sup-

port p' is hinged to the portion a of the truck-frame, so that it can be moved to clear the foot C' of the ladder when the main ladder is elevated, as shown in dotted lines.

70 Rubber cushions q^2 are shown in Fig. 2 in the top of the support p' between the cheeks q , and these cushions are so supported that they press the under side of the ladder at its foot elastically when the ladder is lowered.

75 Cushions q^3 are supported adjacent the turntable against which the lower side of the main ladder c presses when lowered thereon.

80 By pulling upon the rope m^5 , the ladder may be pressed down upon the springs q' and q^3 to permit the cushions in the support p' to be crowded beneath the foot C' , after which the three cushions or springs operate jointly to hold the ladder firmly in transportation.

85 The gate f^4 is swung backwardly as shown in Fig. 1 to elevate the ladder, and the support p' moved to clear its foot.

90 When the ladder D is not extended the weight is sufficient to elevate the ladder to an upright position, the ladder being controlled by the rope m^5 while elevating. The rack-bar is then coupled to the foot, the gate f^4 closed and the turntable may thereafter be turned in any position and the ladder tipped to any required angle.

95 The bracket m with the rack-bar and windlass n^2 move with the turntable and operate upon the ladder in any position of the turntable. The ladder D is extended when in an upright position and such extension changes the center of gravity of the combined ladders, and overweights the free end of the same so that it tends to descend by its own weight when tipped. Such effect is increased by the added weight of the 100 hose which is carried up by the ladder D when extended.

105 The inclining of the ladder from an upright position is controlled by the rack-bar within an angle of 45 to 50 degrees, and when a farther lowering of the ladder is required the rack-bar is detached and the control is maintained by the rope n^3 and the windlass n^2 . The balancing of the extra weight may be effected in any desired degree by an extension-foot C^2 carried upon the ladder-foot C' and adapted to be extended therefrom, as shown in Fig. 12, when additional weight is required upon the foot to counterbalance the extended end of the ladder.

110 In Fig. 12, the extension-foot is shown supplied also with an auxiliary foot C^4 115 adapted to be extended beyond the end of the foot C^2 , so that weights C^5 placed thereon may exert a greater leverage to balance the extension-ladder D , or any load thereon. The extension-foot C^2 is shown as a frame 120

hinged upon the foot C' by a pivot c^3 and braced when in use by detachable rods c^4 having hooks v^1 , v^2 to engage pins v on the foot C^3 , and it can be temporarily lowered 5 to clear the sides of the arch, when adjusting the ladder by shifting the pin to the hook v^2 . (See Fig. 12.)

The portable weights C^5 may be stored on any convenient part of the truck and placed 10 on any part of the foot C' , C^3 , or C^4 , and the auxiliary foot may also be loaded by men pressing upon it when temporary weight is required to elevate or balance the ladder.

As the truck is usually placed parallel with 15 the wall of the building upon which the ladder would be used, an inclination of 45 degrees such as is shown in Fig. 12 is more than sufficient to bring the ladder against the wall of the building, and all movements 20 of the ladder not exceeding 45 degrees can be positively effected by the rack-bar m' .

To increase the stability of the truck when 25 the ladder is in use, adjustable side-braces S are provided, and lifters, as hydraulic jacks T ; both of which are hinged upon the frame of the truck; so that they can be turned into an operative position, or lifted and turned to an inoperative position when in transportation. The braces have each a lineally ex-

30 tended head with lateral ears s , and guide-boxes S' are secured upon the outside of the truck-frames and have grooved edges S' adapted to hold the feet movably. The flanges forming the grooves have notches s^2 35 adapted to admit the head, and the feet may thereafter be slid up and down in the guide-boxes and locked therein by the engagement of a pawl s^3 with rack-teeth s^4 in the back of the guide-box. A hand-screw s^5 is threaded 40 in the head to hold the pawl when engaged with the rack-teeth. A guide-rod S^2 is secured at its ends to the truck-frame at one side of each guide-box, and the foot of the brace has slotted ears s^6 fitted movably 45 to the guide-rod to permit the withdrawal of the ears s from the boxes S' , and to support the brace when the head is disengaged from the guide-box. The brace may then be turned parallel with the side-frames of 50 the truck and supported upon the same to clear the ground while the truck is in transportation, as shown at the right side of the truck-arch in Figs. 1 and 2. At the left side of the arch, one of the braces is shown extended in Figs. 1 and 2.

When it is desired to brace the truck, the head of the brace is inserted in the guide-box and lowered until the brace touches the ground. The pawl is then engaged with the 60 rack-teeth in the guide-box and secured by the screw s^5 . One of the braces in such adjustment is shown in Fig. 4, and widens the base of support so as to greatly increase the stability of the truck and ladder.

65 Where the ground slopes laterally as

shown at A^2 in Fig. 12, or is so uneven that the wheels of the truck do not bear uniformly, the truck may be leveled and supported firmly by hydraulic jacks T or equivalent lifters which are carried by yoke t 70 pivoted to an extended vertical pivot n^7 midway between the side-frames. Such pivoting permits the yoke to be swung outward transverse to either one of the side-frames of the truck to lift or steady the same, and 75 when not in use to be swung in between the side-frames and lifted clear of the ground for transportation.

The yokes are constructed to carry the 80 foot or ram of the hydraulic jack T close to the ground when the yokes are extended in contact with the under side of the truck-frames a or a' , as shown in Figs. 1 and 12.

A vertical screw in the end of the yoke would of course, operate the same as the ram 85 of the hydraulic lifter, and the lifter whatever its nature would thus be operated to press upon the ground and raise or hold either of the side-frames rigidly in the desired position. Such operation of hydraulic 90 jacks is shown in Fig. 12, where the ram of one is projected so as to lift one side-frame, to hold the truck level upon a side-sloping pavement.

The vertically extended pivot permits the 95 yoke when it is not in use, to be swung in between the frames when lifted, and when thus lifted it may be supported upon the hook n^8 upon the side-frames, or by other suitable means. The lifter may be swung 100 under either side of the frame where its operation is desired.

From the above description it will be seen that the invention furnishes a truck in which the ladder may be turned in any direction while elevated to an angle not exceeding 45 or 50 degrees from the vertical, and without any great exertion of power; as the main and extension ladders are balanced by the weight C^2 until the extension 110 ladder is projected. The extension-foot affords means to counterbalance the weight of the extension ladder when projected, and thus enables the rack-bar to control its movements with ease and celerity. 115

The movements of the turntable are made almost frictionless, by the provision of anti-friction rolls upon all its bearing surfaces, and the elevation of the hand-wheels upon the turntable enables the operator to stand 120 upon the turntable while manipulating the hand-wheels and thus to control the inclination and the tipping of the ladder with the utmost certainty.

The ability to counterbalance the ladder 125 effectively at all angles and while inclined in any direction by rotating the turntable, is dependent, of course, upon the arched form of the side-frames which permit the foot of the ladder to swing clear of the frame 130

throughout the entire circle when elevated 45 or 50 degrees.

The counterbalance is made effective by the great elevation of the fulcrum above 5 the pavement which supports the truck, and permits the foot of the ladder to be extended, say ten feet, beyond the fulcrum, and thus make each pound of the counter- 10 balance weight more effective than where 15 the ladder and its foot rotate wholly above the turntable, as in many previous constructions. The elevating of the fulcrum thus increases the leverage of the counterbalance weights, while the arched form of the frame 15 permits the long foot of the ladder to swing around the entire circle without interference.

It is also an important feature of the invention that the rack-bar or other pusher 20 has a positive connection with the foot of the ladder and holds it rigidly in any position to which it is moved by the hand-wheel m^3 .

The screw l^5 shown in Fig. 4 may be made 25 to grip the shaft or sleeve of the hand-wheel and thus lock it from displacement, which operates to hold the pinion rigidly and to maintain the ladder at any angle to which it has been adjusted. A pinion-stop 30 u' is provided at the rear end of the rack m' to limit its movement, and as the gearing is constructed to give the hand-wheel a very great leverage over the pinion so as to effectively control the ladder's movements, 35 such leverage would be liable to overstrain the pinion or break the teeth of the rack, and to avoid such overstrain several teeth are omitted from the rack adjacent such stop, so that the pinion may revolve freely 40 when it reaches the stop. A spring u is applied to the stop to throw the pinion again into mesh with the teeth whenever its motion is reversed to retract the rack-bar.

The attachment of the hose to the extension ladder D enables this extension ladder and truck to perform some of the functions of a water-tower, in carrying the hose automatically to any point which the operator can reach by the ladder. By elevating the 45 hose automatically, much time and strain on the part of the operator is avoided, as he can ascend the ladder when it is adjusted at the desired point and then manipulate the nozzle in the manner desired.

50 The construction differs from a water-tower and has certain advantages over the same, in its ability to carry the hose-nozzle to the side windows of a building where the sides of the building itself are not accessible to a truck, and could not therefore accommodate a water-tower in front of such side windows. Such a relation of the ladder to side windows z of a building z' , is shown in Fig. 14, where the truck is shown 55 located at the end of a building (as upon

one street), and the ladder projected past the side of the building, as through an alley or passageway, so that the operator may direct the hose into the windows z . The connection of the hose with the extension 70 ladder thus enables it to operate where a water-tower could not gain access to a window.

Fig. 14 shows the hose extended through the gap g of the truck, and this is also represented by a section of the hose y extending through the gap in Fig. 5. The hose extends downward through the gap to the ground where coils y^3 are shown which would permit the elevation of the hose with the extending ladder, and the end y^4 of the hose would be connected with the water-supply. The ladder is extended before the water is turned in the hose, and as the weight which would be produced by the water could be 85 known by experiment the weights may be supplied to the extension-foot or auxiliary-foot c^4 to balance the same, so that the ladder would still be balanced when the hose is in 90 operation.

The chief difficulty in manipulating such aerial ladders has heretofore lain in the insufficient balancing of such ladder, which can only be obtained economically by the construction shown herein where the turntable is greatly elevated above the ground 95 and the foot of the ladder permitted to swing through the same, so as to carry weights at a considerable distance from the fulcrum, and thus secure the balancing of the ladder 100 by increasing the leverage rather than increasing the weight.

Having thus set forth the nature of the invention what is claimed herein is:

1. In a counterbalanced aerial safety ladder and truck, the combination, with a truck having a frame with elevated arch at each side, of a turntable sustained upon the frames at the top of the arches and having a gap in one side, the framing of the truck having also a corresponding gap, and a ladder having a horizontal fulcrum upon the turntable and an extended foot movable in the said gaps to an upright position and weighted to balance the said ladder, and the truck-frame 110 thus permitting such ladder and the extended foot to revolve to any point of the compass.

2. A counterbalanced aerial safety ladder and truck having arched side-frames with an annular turntable-seat upon such frames, a turntable fitted to such seat, the seat and turntable having each a gap in one side, and a ladder having a horizontal fulcrum upon the turntable close to the same and having 120 an extended foot movable through the said gaps and weighted to balance the ladder.

3. In a counterbalanced aerial safety ladder and truck, the combination, with the truck, of an annular turntable-seat sus- 125

- 6
- tained upon the same with gap in one side, a turntable fitted to the said seat and provided with gap at the middle extending through one side, a ladder pivoted upon the turntable with extended foot movable through the said gaps and weighted to balance the ladder, and a section of the seat fitted removably to the gap in the seat to complete the support for the turntable when the ladder is erected.
4. In a counterbalanced aerial safety ladder and truck, the combination, with the truck, of an annular turntable-seat sustained upon the same with gap in one side, a turntable fitted to the said seat and provided with gap at the middle extending through one side, a ladder pivoted upon the turntable with extended foot movable through the said gaps and weighted to balance the ladder, and a section of the seat fitted removably to the gap in the seat to complete the support for the turntable when the ladder is erected, and the turntable-seat, including the removable section, provided with anti-friction rolls to support the turntable against upward, downward and lateral thrusts.
5. In an extension ladder and truck, the combination, with the truck, of an annular turntable-seat sustained upon the same with gap in one side, a turntable fitted to the said seat and provided with gap at the middle extending through one side, a ladder pivoted upon the turntable with extended foot movable through the gaps and weighted to balance the ladder, a stand for an operator upon the turntable, and separate trains of gearing arranged for the operator to rotate the turntable and also to move the ladder upon its pivot.
6. In an extension ladder and truck, the combination, with the framing of the truck, of a turntable sustained upon the same with gap for the passage of the ladder through the same and an extension ladder having a horizontal fulcrum upon the turntable and foot extended through the gap and having an arm extensible below the turntable and provided with means for supporting weights to balance the extended section of the ladder.
7. In an extension ladder and truck, the combination, with the truck having side-frames, of a turntable sustained upon the same with gap in one side, the truck having between its side-frames a corresponding gap, a ladder pivoted upon the turntable and having an extended foot movable through the said gaps and weighted sufficiently to elevate the ladder to an upright position, and means for tipping the ladder positively from such upright position to any desired angle.
8. In an extension ladder and truck, the combination, with the truck having side-frames, of a turntable sustained upon the same with gap in one side, the truck having between its side-frames a corresponding gap, a ladder pivoted upon the turntable and having an extended foot movable through the said gaps and weighted sufficiently to elevate the ladder to an upright position, a bracket projected downwardly from the turntable, a pinion supported rotatably thereon, a wheel upon the turntable with connections for an operator to rotate the said pinion, a rack-bar fitted to the pinion and a coupling adapted to connect one end of the rack-bar detachably to the foot of the ladder, whereby the rotation of the said pinion inclines the ladder upon its pivot.
9. In an extension ladder and truck, the combination, with a truck having trussed and arched side-frames, of a turntable sustained upon the frames above the arches and having a gap in one side, the truck having between the side-frames a corresponding gap, a ladder pivoted upon the turntable with weighted foot movable through the said gaps, an elastic support secured upon the truck to sustain the upper part of the ladder when lowered, and a support movable upon the truck to wedge beneath the said foot at such time, to press and hold the ladder rigidly upon the truck.
10. In an extension ladder and truck, the combination, with a truck having arched side-frames, of a turntable sustained upon the frames above the arches and having a gap in one side, the truck having upon its center line a corresponding gap, a ladder pivoted upon the turntable with weighted foot movable through the said gap, a support secured upon the truck and provided with an elastic cushion to sustain the upper part of the ladder when lowered, an elastic cushion upon the turntable to also contact with part of the main ladder when lowered, and a support movable upon the truck to wedge beneath the said foot at such time, and provided with an elastic cushion, whereby the entire ladder is elastically supported for transportation.
11. In an extension ladder and truck, the combination, with a truck having trussed and arched side-frames, of a turntable sustained upon the frames above the arches, a ladder pivoted upon the turntable, means for elevating the ladder, bracket-braces having pivotal connection with the side-frames and movable vertically thereon, and means to lock the braces when adjusted in contact with the ground.
12. An extension ladder and truck having arched side-frames with sloping sides to the arches, a turntable sustained upon the frames above the arches and having a gap in one side, a ladder pivoted upon the turntable with foot movable through the gap and weighted to hold the ladder upright.

and means movable with the turntable for tipping the ladder, the inclined sides of the arches clearing the ladder when the ladder is held in an inclined position and the turntable rotated.

13. In an extension ladder and truck, the combination, with the truck having side-frames, of a turntable sustained upon the same with gap in one side, the truck having between its side-frames a corresponding gap, a ladder pivoted upon the turntable and having an extended foot movable through the said gaps and weighted sufficiently to elevate the ladder to an upright position, a bracket projected downward from the turntable with a pusher supported movable thereon, a wheel upon the turntable with connections to operate the pusher, a coupler on the pusher, and a coupler on the ladder to connect one end of the pusher detachably to the foot of the ladder to move the same through a limited arc, and a windlass upon the bracket with rope connected detachably to the foot of the ladder for controlling its movement beyond the said arc.

14. In an extended ladder and truck, the combination, with the truck, of a turntable sustained upon the same with gap in one side, the framing of the truck also having upon its center line a corresponding gap, a ladder having horizontal pivot upon the turntable and an extended foot movable in the said gaps to an upright position and weighted to counterbalance the ladder, and a windlass and rope attached to the ladder on the side opposite such foot to control the elevation of the ladder to an upright position.

15. In an extension ladder and truck, the combination, with the truck, of a turntable sustained upon the same with the ladder pivoted thereon, vertical guide-boxes upon the sides of the frame provided with guides for the head of a brace and a rack to lock the same in the guide-box, braces having each a head movable in the guide-box and detachable therefrom, and having a pawl to engage the rack in the guide-box when the brace is in contact with the ground.

16. In an extension ladder and truck, the combination, with a truck having upright truss-frames upon the sides, of vertical guide-boxes secured upon the outer sides of the frames with vertical guide-rods adjacent thereto, braces having feet movable in the said guide-boxes and removable therefrom, and slotted lugs upon the braces embracing the guide-rods, whereby the braces may be swung inwardly upon the guide-rods when their feet are removed from the guide-boxes.

17. In an extension-ladder, the combination, with the truck, of a turntable sustained upon the same with ladder pivoted thereon, vertical guide-boxes upon the sides of the frame, braces having feet movable in

the said guide-boxes, rack-teeth in the back of the guide-boxes, a pawl upon each of the braces to fit such rack-teeth and a screw adjacent to the pawl to hold it in the rack-teeth when the brace is adjusted.

18. In an extension ladder and truck, the combination, with the truck, of an annular turntable-seat sustained upon the same with a gap in one side, a turntable fitted to the said seat and provided with a lateral gap, anti-friction rolls supported upon such seat, internal rack-teeth upon the inner edge of the seat, a gate fitted removably to the gap and provided also with anti-friction rolls and with a corresponding section of the internal rack, a pinion journaled upon the turntable and meshing with the said internal rack, and a hand-wheel above the turntable for turning such pinion.

19. In an extension ladder and truck, the combination, with the truck, having a turntable sustained upon the side-frames and a ladder pivoted upon the turntable, of the vertical pivot n^7 supported midway between the side frames of the truck, the yoke t pivoted thereon and extended when turned outwardly under and beyond the side frame, and a lifter affixed to the end of the yoke, and operable to press upon the ground and to crowd the yoke upwardly against the under side of the side frame.

20. In an extension ladder and truck, the combination, with the truck having a turntable sustained upon side-frames and a ladder pivoted upon the turntable, of an extended vertical pivot supported between the frames of the truck, a yoke pivoted thereto and movable vertically thereon and extensible under and beyond the side-frames, a lifter affixed to the end of the yoke to press upon the ground, and means for hanging the yoke and lifter upon the frame when swung within the same and slid upwardly upon the pivot.

21. In an extension ladder and truck, the combination, with a truck having side-frames with level ends a , a' and arches connecting the same, of a turntable sustained upon the frames above the arches, a ladder pivoted upon the turntable with weighted foot movable downward through the turntable, and a flight of stairs extending from the level portion of the truck to the said turntable.

22. In an extension ladder and truck, the combination, with the truck having side-frames, of a turntable sustained upon the same with gap in one side, a ladder pivoted upon the turntable, a hose having its nozzle-end attached to the ladder, and the hose extended through the gap in the turntable for connection to the water-supply.

23. In an extension ladder and truck, the combination, with the truck having side-frames, of a turntable sustained upon the

same with gap in one side, a main ladder pivoted upon the turntable and having an extension ladder D movable thereon and an extended foot movable through the said gap and weighted sufficiently to elevate the ladders to an upright position, mechanism for tipping the ladder positively from such upright position, a hose attached to the extension ladder, and supports upon the main ladder to hold the hose and permit its extension with the extension ladder.

24. In an extension ladder and truck, the combination, with a truck having side-frames with ends *a*, *a'* and arches connecting the same, of tie-bars connecting the side-frames, a turntable sustained upon the frames above the arches, a ladder pivoted upon the turntable with weighted foot movable downward through the turntable and a reach connecting the ends of the truck below the turntable to brace the arches of the truck.

25. In an extension ladder and truck, the combination, with a truck having side-frames with ends *a*, *a'* and arches connecting the same, of tie-bars connecting the side-frames, a turntable sustained upon the frames above the arches, a ladder pivoted upon the turntable with weighted foot movable downward through the turntable, a reach connecting the ends of the truck below the turntable to brace the arches of the truck, and a bracket extended downward from the turntable and having a bearing upon the said reach.

In testimony whereof we have hereunto set our hands in the presence of two subscribing witnesses.

WILLIAM McMANE.
BENJAMIN F. CARPENTER.
